UNITED STATES PATENT OFFICE.

JOSEPH A. SKOGLUND, OF ST. PAUL, MINNESOTA.

BRUSH.

Application filed December 14, 1925. Serial No. 75,232.

My invention relates to brushes and the method of forming the same and particularly to brushes of the type in which the bristles are mounted in a flexible back 5 adapted to be folded upon itself to shield the bristles when the device is not in use.

An object of the invention resides in extending the marginal end portions of the back beyond the bristles and in attaching 10 fastening members thereto, which serve to hold the back folded in flattened compacted form with the bristles intermeshed.

Another object resides in providing a retaining hand strap which extends from end 15 to end of said back and is secured thereto by means of said fastening members, both said strap and back being punched to receive said fastening members prior to the attachment of the strap to said back to insure the proper amount of slack in said 20 strap so that it will not interfere with the folding of the back and yet fit snugly around the same when folded.

With the foregoing and other objects in 25 view, which will appear in the following description, the invention resides in the novel combination and arrangement of parts and in the details of construction hereinafter described and claimed.

30 In the drawings illustrating my invention in one form:

Fig. 1 is a perspective view of my improved brush showing the same extended.

Fig. 2 is a perspective view of the brush 35 folded.

Fig. 3 is an enlarged elevational view of the structure as shown in Fig. 1.

Fig. 4 is an enlarged elevational view of the structure as shown in Fig. 2.

40 With flexible folding brushes considerable difficulty is encountered in causing the backs of the brushes to lie flat when folded and held together by the ordinary methods, such methods usually producing bulky and unsightly parcels. In my improved brush the back is held folded in flattened compacted form by means of fasteners which are directly secured to the back itself having their co-operating portions disposed on 45 the facing portions of the surface of said back in which the bristles are imbedded. In addition it has been found to involve great care and exactness in attaching the straps to the brushes so that the same will 50 not be too tight or loose when the brush is folded. This difficulty, I overcome by

first punching the fastening member holes in the back and strap the proper distance apart by means of punches, preferably those having pairs of properly spaced dies, and thereafter assembling and attaching the fasteners so that said straps are uniformly 60 of the proper length and properly attached to the back, making all of the brushes uniform. 65

The brush proper as shown in Figs. 1 and 3 comprises a back A composed of two plies of resilient material 10 and 11, secured together by cementing, or any other suitable method. In the inner ply 11 is set bristles 12 which may be of wire or other suitable material which are secured to said ply by any of the methods now in common use for this purpose. If desired wire staples may be used which penetrate the ply 11 from the rear, protruding outwardly therefrom, the base portion of said staples being lodged between the two plies 10 and 11 of back A. The outer ply 10 serves merely as a covering for concealing the ends of the bristles 12 and may be made from embossed leather, 70 rubber or other material formed to give an ornamental and attractive appearance to the brush. The bristles 12 are confined medially of the back A leaving marginal end portions 13 and 14 extending outwardly beyond said bristles. The corners of the back A are rounded as indicated at 15 to give the brush a finished and neat appearance. 75

To facilitate using the brush, a strap 16 80 is employed which extends longitudinally of the brush from end to end thereof and is secured thereto by means of fastener members 17 and 18, which are riveted or clinched upon said back at the marginal portions 13 and 14 thereof as clearly shown in Fig. 1. This strap is of a length greater than the back A so that when the brush is extended as shown in Figs. 1 and 3, the hand of the user may be inserted between 85 said strap and back permitting the brush to be readily manipulated by the user for the particular purpose desired. 100

When the brush is not in use, the same may be folded transversely upon itself across 105 the middle thereof as indicated at 19 in Figs. 2 and 4 dividing the back A into two facing portions 20 and 21 which serve to shield the bristles 12 positioned between the same. The portions 19 and 20 are held together 110 by means of the fastener members 17 and 18 previously referred to which are attached

to the marginal end portions 13 and 14 of said back and which have co-operating snap portions 22 and 23 disposed upon the surface of said back from which the bristles 12 protrude so that when the portions 19 and 20 are folded, these co-operating fastener members may be snapped together in the usual manner to hold the parts as illustrated. With the particular disposition of the fastener members 18 and 19 upon the marginal portions 13 and 14 of back A and with these portions facing one another the same may be secured together in close relation to one another which has the effect of bending the portions 20 and 21 and the marginal portions 13 and 14 of back A so as to form reverse curves therein, causing the brush to remain folded in compacted and flattened form, the bristles 12 thereof being intermeshed and shielded by the opposing portion of said back. Intermeshed, the bristles 12 lend firmness to the folded brush by opposing relative movement between the facing back portions in their own planes.

The strap 16 is made of such length that when the back A of the brush is folded over, said strap fits snugly around said back being neither too tight nor too loose. Where the strap is sewed on, the operator has to guess at the proper position of the strap and the proper position of the seam so that in many of the devices so manufactured the straps are either too loose and produce an unsightly article or are too tight and prevent the brush from closing properly or from becoming flattened and compacted. With my present invention I overcome this disadvantage as follows: Two sets of punches are employed for punching the holes in both the strap and back for receiving the fastener members 17 and 18. These punches have individual dies for simultane-

ously punching both of the holes in each of said members, said dies being spaced the proper distance apart so that when the back and strap are assembled and the fastener members inserted in the holes so punched said straps are of the proper length to fit snugly around the back A when the same is folded. In this manner the brushes may be manufactured so as to be of uniform construction, and appearance.

My improved brush is simple in construction and may be readily manufactured. It is effective and efficient in use and may be folded up to shield the bristles and when so folded provides a compacted, flat, neat appearing and attractive article.

What I claim is:

1. A brush comprising a flexible back, bristles mounted on the inner side of the back between relatively deep marginal end portions thereof, said back being adapted to be folded upon itself medially to shield the bristles between opposed portions of the back, and co-operating fastener members directly secured to said end portions within the confines thereof adapted to hold said end portions together, face to face, in flattened condition, with the bristles on said portions of the back intermeshed. 60

2. A brush comprising a flexible back, bristles mounted on said back at the inside thereof, said back being adapted to be folded upon itself to shield said bristles, the marginal end portions of said back extending beyond the bristles, and co-operating fastening members secured to said marginal portions serving to hold the back folded and a strap across said back secured thereto by 75 said fastening members. 80

In testimony whereof, I have signed my name to this specification.

JOSEPH A. SKOGLUND.
